UNITED STATES PATENT OFFICE

169,973

COMBINED DESK AND COUNTER

Walter D. Goins, Sr., Birmingham, Ala.

Application August 13, 1952, Serial No. 20,989

Term of patent 14 years

(Cl. D80—9)

To all whom it may concern:

Be it known that I, Walter D. Goins, Sr., residing at Birmingham, in the county of Jefferson and State of Alabama, have invented a new, original, and ornamental Design for a Combined Desk and Counter, of which the following is a specification, reference being had to the accompanying drawing, forming part thereof, in which

Fig. 1 is a top plan view of a combined desk and counter, showing my new design; Fig. 2 is a rear elevational view; Fig. 3 is a front perspective view; and Fig. 4 is an end elevational view, the opposite being similar in appearance.

I claim:

The ornamental design for a combined desk and counter, as shown and described.

WALTER D. GOINS, SR.
